Primary Examiner — Brandon M Rosati*Assistant Examiner* — Marissa J Cash(74) *Attorney, Agent, or Firm* — McDermott Will & Emery LLP(57) **CLAIM**

I claim the ornamental design for a balloon support, as shown and described.

DESCRIPTION

FIG. 1 is an isometric view of a balloon support according to a new design.

FIG. 2 is an inverted isometric view of a detail of the balloon support shown in FIG. 1.

FIG. 3 is a left side view of the balloon support shown in FIG. 1.

FIG. 4 is a right side view of the balloon support shown in FIG. 1.

FIG. 5 is a front view of the balloon support shown in FIG. 1; and,

FIG. 6 is a rear view of the balloon support shown in FIG. 1.

In the drawings, the broken lines depict environmental subject matter only and form no part of the claimed design.

1 Claim, 4 Drawing Sheets(56)
